(57) **CLAIM**

The ornamental design for an integrated audio/video call control pod, as shown and described.

DESCRIPTION

FIG. 1 is a perspective view of an integrated audio/video call control pod showing the top and left side of our new design; FIG. 2 is a front plan view of the integrated audio/video call control pod of FIG. 1;

FIG. 3 is a rear plan view of the integrated audio/video call control pod of FIG. 1;

FIG. 4 is a left side plan view of the integrated audio/video call control pod of FIG. 1; the right side plan view is a mirror image of the left side view and is therefore not shown; FIG. 5 is a top view of the integrated audio/video call control pod of FIG. 1; and,

FIG. 6 is a bottom view of the integrated audio/video call control pod of FIG. 1.

The broken line showings in FIG. 6 are for illustrative purposes only and form no part of the claimed design.
